UNITED STATES PATENT OFFICE.

ABBOTT ALLEN, OF DUNELLEN, AND THOMAS J. MUMFORD, 2D, OF PLAINFIELD, NEW JERSEY, ASSIGNEES, BY MESNE ASSIGNMENTS, TO ROSE S. MUMFORD, OF PLAINFIELD, NEW JERSEY.

MOLDING MACHINE.

Application filed June 30, 1917. Serial No. 178,001.

To all whom it may concern:

Be it known that we, ABBOTT ALLEN, of Dunellen, county of Middlesex, and State of New Jersey, and THOMAS J. MUMFORD, 2d, of Plainfield, county of Union, and State of New Jersey, have invented certain new and useful Improvements in Molding Machines, of which the following is a specification.

10 This invention relates to molding machines and particularly to that type of molding machines known as a jolt roll over pattern draft machine, in which the sand in the flask is rammed or packed on a jolt 60 ramming machine and picked up and rolled over to inverted position above means for drawing the mold i. e., separating the pattern from the mold.

This general type of machine is old in the 20 molding machine art, but the previously known machines of this class are defective in that damage to the sand mold very frequently occurs in separating or drawing the pattern, for reasons which will appear herein- 70 after. It is one of the primary objects of 25 our invention to provide an improved jolt roll over pattern draft machine by means of which the pattern may be drawn without injury to the sand mold. In this connection, our invention contemplates the 30 provision of an improved pattern drawing mechanism; an improved leveling device; and the provision of means whereby the carrier or roll over mechanism, when moved 35 to inverted position, is supported in such manner that there is no load carried thereby at the time of the drawing of the pattern, for purposes which will appear.

Another object of our invention is the 40 provision of improved means for automatically locking the mold parts to the roll over mechanism, and in the provision of improved means for automatically actuating the pattern mechanism.

45 The foregoing, together with such other objects as may hereinafter appear or are incident to our invention, is accomplished by means of the construction illustrated in preferred form in the accompanying drawings, wherein—

Figure 1 is a plan view of a jolt roll over pattern draft machine embodying our invention; Fig. 2 is a side elevation partly broken away of the machine shown in Figure 1, with certain of the parts shown in

cross-section; Fig. 3 is a sectional view illustrating certain details of the invention; Fig. 4 is an enlarged plan view and partial section of one of the devices for automatically locking the mold parts to the roll over mechanism; Figs. 5, 6, and 7 are sectional details; and Figure 8 is a partial side elevation and section of a locking mechanism used in carrying out our invention.

Referring now particularly to Figures 1 and 2, it will be seen that the machine comprises a single base 7 upon which is mounted a jolt ramming mechanism 8 of any preferred type; a pair of supporting frames or standards 9 on which is pivotally carried a roll over mechanism indicated as a whole at A; and a pattern drawing and leveling device indicated as a whole at B.

The roll over mechanism will be first described. This mechanism comprises a pair 75 of arms 10 preferably formed integrally with a sleeve 11 adapted to be rotatably carried by the shaft 12 supported in the upper ends of the standards 9. The arms 10 extend along each side of the jolt ramming 80 machine 8 and are braced at their outer extremities by means of the rod 13. The arms are rotated about the shaft 12, to assume an inverted position, by means of the piston 14 working in the cylinder 15 swingingly mounted on the base of the machine between the standards 9, through the medium of the piston rod 16, a pair of lever arms 17 and an eccentric shaft 18 which is carried by the arms 17 and to which is coupled the piston rod 16. The sleeve 11 is provided with a pair of shoulders 19 adapted to come against the adjustable stops 20 to limit the movement of the roll over 90 mechanism when turned to inverted position.

The means for supporting the mold parts and securing them to the roll over mechanism will now be described. The pattern plate 21, i. e., the board which carries the 100 pattern, is provided at each end with a downwardly depending strap 22 and secured to each of these straps, so as to project downwardly therefrom, are a pair of pins 23 each of which passes through a lug 105 or shoulder 24 carried on the arms 10. These lugs 24 also slidably support a locking rod 25, there being one of such locking rods for each arm. Each locking rod is provided with a pair of collars 26, each of 110

which carries a pin 27 adapted to be passed through the hole 28 formed in each pin 23. The rods 25 are provided with springs 29 adapted to move the rods to the right 5 causing the pins 27 to pass through the openings 28, thus locking the pattern plate 21 to the arms 10. When, however, the parts are in the position indicated in Figure 2, the rods are held in unlocking position 10 by means of a pair of cam members 30 attached to the standard 9 each of which cams is adapted to be engaged by the rollers 31 carried on the end of each rod 25. As the roll over arms are being brought 15 back from inverted position to the position shown in Figure 2, the rollers 31 engage the ends of the cam members 30 and shift the rods 25 to the left in an amount sufficient to withdraw the pins 27 from the holes 28 20 in the pins 23.

The operation of the parts thus far described will be set forth before passing to the pattern draft mechanism.

Assuming that the parts are in the position indicated in Figure 2, in which position 25 the rods 25 have been shifted to the left by the cam members 30 an amount sufficient to free the pins 27 from the pins 23, the pattern plate 21 with its pattern rests upon the 30 top of the jolt ramming table and the arms 10 with their associated parts lie slightly below the level of the table. A flask is then placed over the pattern plate 21 and filled with sand, and, the pins 23 being unlocked, 35 the jolt ramming mechanism can be actuated to impart a jolting reciprocating movement to the mold parts in order to ram the sand, without impacting in any manner on the roll over arms 10, the pins 23 being 40 slidable in the lugs 24.

After the mold has been rammed, air is introduced into the cylinder 15 in any preferred manner, and the piston 14 begins to move downwardly causing the arms 10 to 45 swing upwardly until the lugs 24 come against the straps 22 of the pattern plate 21, and when this occurs, the holes 28 in the pins 23 will come opposite the pins 27. As the upward movement continues, it will be 50 apparent that the arms swing away from the cam members 30, which permits the springs 29 to force the rods 25 to the right, thus causing the pins 27 to enter into the holes 28 in the pins 23, the complete locking 55 movement being accomplished when the rollers 31 leave the cams 30. The mold parts are now securely locked to the roll over arms because the pattern plate is locked to the arms by means of the pins 27 and 23, 60 and the bottom board 32 and flask 33 are clamped to the pattern plate by means of clamps as is well understood in this art.

In order to insure the moving of the rods 25 to locking position, the ends of the cam members 30 are claw-shaped, in such man-

ner as to engage the rollers 31 on opposite sides when the parts are in the position indicated in Figure 2. By making the ends of the cam members 30 claw-shaped, when the arms 10 are initially raised, a positive movement to the right is imparted to the rod members 25 by the claws, this resulting from the fact that with the shaft 12 as an axis of rotation, the arms 10 will swing away from the cam members 30 which will cause the rods 25 to move to the right since the rollers 31 are temporarily held by the claws. 75

Compressed air is introduced into the cylinder 15 until such time as the moving parts have passed dead-center, after which the weight of the moving parts is sufficient to complete the inverting movement, the balance of the stroke being gradual and easy because the air in the cylinder 15 is slowly exhausted so as to control this remaining movement of the parts, and until such time as the shoulders 19 come against the stops 20. The flask 33 is now supported with the bottom board 32 down in the dotted line position indicated above the pattern drawing mechanism B. When the roll over arms are in this inverted position, they support the weight of the mold and its parts and this may be in the neighborhood of 3000 95 pounds or more, which will of course, deflect or bend the arms because it would be impossible to construct the arms 10 so that they would not spring under the weight of the mold parts, without making the arms of a size and weight which would be absolutely prohibitive to economical construction, and economical and effective operation. 100

It will be apparent that this whip or springing of the roll over arms is an item of important consideration in the drawing of the pattern, for reasons which will be readily understood by those familiar with the art and it is in connection with this that machines of this type have been deficient. The difficulties encountered in this connection are overcome by our improved pattern drawing mechanism which will now be described. Suitably supported from the base 7 of the machine is a main cylinder 34 having a reservoir 35 filled with oil. A vertically moving plunger 36 is mounted in the cylinder and is provided with a groove 37 in the side, the lower end of which opens beneath the plunger 36, and is controlled by a valve mechanism C to be hereinafter described. 110

The plunger 36 carries a hollow head 38, which at each of its four corners is provided with a cylinder 39 in each of which is mounted a vertically movable leveling plunger 40. Air is supplied to the main cylinder 34 by a pipe 41 from which leads a branch 42 which supplies the four cylinders 39 as will be seen on inspection of Fig- 125 130

ures 1 and 2. The branch 42 is controlled by a valve 43 normally held in closed position, but opened by the adjustable abutment 44 mounted on the rod 45 attached to the head 38.

In operation air is admitted by suitable valve mechanism to pipe 41, and entering the cylinder 34 acts upon the top surface of the oil therein contained and forces the oil 10 through the groove 37 and past the valve mechanism C into the space beneath the plunger 36, thus causing the plunger 36 to rise carrying with it the head 38 and its associated parts. The upward movement 15 continues until such time as the valve C comes against the stop 46 and when this takes place the valve C is depressed until such time as the stop comes against the piece 53, which latter piece limits the upward movement of the plunger, and the parts are held in upper position by the compressed air, the head occupying the position indicated in dotted lines in Figure 2, a position in which the head is some distance below 20 the bottom board 32. The valve C, however, does not completely close but leaves a greatly restricted orifice.

When the plunger 36 reaches the limit of its upward movement, the abutment 44 30 strikes the stem of the valve 43 and admits air through the branch 42 into the bottom of the cylinders 39 which causes the plungers 40 to rise until they come into engagement with the bottom face of the bottom board 32.

Before releasing the clamps which serve to hold the bottom board and flask in position on the roll over mechanism, preparatory to the separation of the pattern plate 40 and pattern from the sand mold, we utilize the pistons 40, as a means for supporting the weight of the mold parts, in such manner as to take out the spring in the arms 10 caused by the weight of the mold parts. We 45

accomplish this by placing in the branch 42 an automatic adjustable pressure maintaining valve 47, which may be of any preferred type on the market, and which serves to maintain the pressure in the cylinders 39 50 at any predetermined point. To illustrate, the line pressure in most foundries is 80 pounds per square inch, and this with a given area of the pistons 40 would exert a given amount of lifting power. In most 55

cases this would be too much and would cause the pistons 40 to actually lift the roll over mechanism and free the shoulders 19 from the stops 20 which would, of course, immediately cause difficulties when the bottom board and flask were unclamped and lowered away from the pattern plate and its pattern. The operator either by calculation or rough estimate can arrive at an approximation of the weight of the mold, flask 60

and bottom board, and by means of a dial 65

or diagram provided for the purpose, can determine how many pounds of pressure should be maintained in the branch 42 in order to cause the pistons 40 to exert a lifting force equivalent to the approximated weight of the mold, and he sets the automatic pressure maintaining valve 47 at the required pressure. This, of course, is done before the main plunger 36 is elevated or immediately thereafter, and in this connection it is to be observed that the weight of the mold need be approximated only within 100 pounds or so as the arms 10 are sufficiently rigid as to not spring under such a load.

It will be clear therefore, that with the valve 47 set to maintain the proper pressure in the cylinders 39, the pistons 40 after having initially come into engagement with the bottom board 32, will approximately balance the weight of the mold parts, and relieve the roll over arms of such weight, as a result of which the bending or springing will be taken out of the arms 10, and they will lie absolutely horizontal, i. e., in a plane at right angles to the vertical plane of the movement of the plunger 36.

After the plunger 36 has been raised to elevate the head, and after the pistons 40 have moved upwardly to engage the bottom board 32 and to take up the load of the mold parts, the operator admits air into the cylinders 48 which causes the pistons 49 to move upwardly to actuate the toggle mechanism 50 adapted to force the arms 51 against the pistons 40, thereby locking the pistons in their raised position. It will, of course, be understood that for each pair of pistons 40 there is provided a cylinder 48, toggle mechanism 50 and a pair of arms 51.

The parts are now in position for the pattern drawing operation, to accomplish which the clamps are removed and pressure exhausted from the main cylinder 34 which allows the plunger 36, the head 38 and the pistons 40, to move downwardly carrying with them the bottom board and flask. The pattern plate, however, being locked to the arms, it will be seen that the mold is separated from the pattern and pattern plate.

When the pattern drawing mechanism reaches bottom position, the roll over arms are swung back to position shown in Figure 2, the completed half mold is removed, a new flask placed in position, filled with sand and rammed; after which the operation is repeated as above set forth, the pistons 40, after the removal of the mold being unlocked by introducing air on the upper side of the pistons 49 and exhausting pressure from the lower side, and by the exhausting of the pressure in the cylinders 39.

The valve mechanism C which has heretofore been mentioned comprises a stem 52 slidable in the block 53; a shoulder 54, a

valve member 55 adapted to close the port 37^a constituting the means establishing communication between the groove 37 and the space beneath the plunger 36. The valve 55 is held in the position as indicated in Figure 7, by means of the spring 56 in which position oil can freely circulate. When, however, the stem 52 takes against the stop 46, the port 37^a is partly closed, and circulation 10 of the oil is materially restricted, as previously indicated, for a purpose to be set forth.

It will be apparent that the movement of the plunger as it approaches the upper end 15 of its stroke should be retarded and for this reason the valve 55 is given the peculiar shape shown so that when the stem 52 takes against the stop 46 and is depressed, the valve, by reason of its shape, gradually 20 restricts the opening 37^a, thus gradually slowing up the movement of the plunger and the parts carried thereby, which prevents injury thereto. It will also be noted that by this same arrangement, the initial downward 25 movement of the plunger and its associated parts is slow, and furthermore, normally accelerated. The draw is thus effected at a slow rate and without injury to the mold.

It will also be apparent that it is desirable 30 able to slow up the movement of the plunger as it approaches the lower extreme of its stroke in order to prevent injury to the parts and to the mold. This is accomplished by providing a small reservoir 59 in the bottom 35 plate 60 of the cylinder 34 and mounting within the reservoir a floating piston member 61 having a stem 58 which is normally caused to project into the main cylinder 34 by means of the spring 62, there being 40 a restricted port 63 arranged in the parts 61 and 58 so as to permit circulation from the small reservoir 59 into the main cylinder. A plug 57 is screwed into the bottom of the plunger 36, and in operation, when 45 the plunger 36 reaches the last portion of its stroke, the plug 57 strikes against the stem 58 and forces the stem and the piston 61 downwardly, the movement, however, being slow because of the restricted port 63, 50 through which the oil in the reservoir 59 must be forced into the cylinder 34. The relatively small flow of oil which can take place through the restricted port slows up the downward movement of the plunger 36 55 so that no appreciable shock is transmitted to any of the parts.

It will of course be understood that when the plunger moves downwardly the stop 44 moves out of contact with the stem of the 60 valve 43, and such valve closes.

It will be apparent from the foregoing that the machine operates efficiently and economically, and is practically fool-proof because of the automatic character of its operation. It will be apparent that no injury

to the molds can take place during the drawing and lowering away because the initial and the closing operations of the downward travel are very slow, uniformly accelerated and gradually arrested.

Also as set forth, the relieving of the roll over mechanism of the weight of the mold parts absolutely insures a draw at right angles with the plane of the pattern, which will eliminate the breaking and defacement 75 of the mold cavity, which would otherwise take place when the arms would whip or spring back to normal position, when the arms were relieved of the weight of the mold parts.

Again, it is to be noted that by the use of four independent leveling pistons, with their common operating power of such a character as to allow the pistons to move independently of one another, the pistons automatically accommodate themselves to any irregularities in the bottom board such as would be present in a bottom board which was warped or otherwise defective. By this arrangement the bottom board is not only engaged at four separate points, but is engaged with equal pressure, so that regardless of inequalities or irregularities in the bottom board, the bottom board will always be supported, and thus the flask will always be supported in absolutely the same position they occupied when clamped to the pattern plate in inverted position, immediately previous to the draw. This also ensures a perfect draw. Another very important advantage is that it is unnecessary to make any adjustment for varying depths of flasks. It is also immaterial whether the centers of gravity of the mold and the pattern drawing mechanism coincide.

The eccentric 18 is provided in order to increase or decrease the length of the lever arm 17, in accordance with variations in the load to be handled by providing the eccentric with the plurality of holes 64, the eccentric being mounted so that any one of said holes may be shifted so as to engage the pin 65, which obviously will result in altering the length of the lever arms, and thus altering the leverage exerted.

As a means for preventing injury and possible breakage to the leveling device, in the event of breakage of the air feed line, or other stoppage of the supply of fluid pressure when the mold parts are being supported by the leveling device we provide an automatic locking device for holding the toggles 50, arms 51 in locking position. This device is shown on an enlarged scale in Figure 8, from an inspection of 110 which it will be seen that the piston rods 49^a of the locking pistons 49 which work in the cylinders 48 are provided with an inclined abutment 49^b. Associated with each locking cylinder 48 is a second cylinder 52' 115

in which works a piston 53' provided with a piston rod 54' carrying at its outer extremity a wedged member 55' which is adapted to be thrust between the abutment 5 49^b and the head of its respective cylinder 48, thereby holding the toggles in locking position. The operation is as follows. After the leveling plungers have been moved into engagement with the bottom board, 10 pressure is admitted into the cylinders 48 beneath the plungers 49 and flows from the cylinders 48 through the ports 56' into the cylinders 52', forcing the pistons 53', the piston rods 54' and the wedges 55' to the 15 right into locking position, this movement being assisted by the springs 57'. After the mold has been drawn and removed, the leveling plungers are released by introducing pressure into the cylinders 48 above the 20 pistons 49, and when this occurs the pressure flows through the ports 58' into the cylinders 52' and forces the pistons 53', piston rods 54' and the wedges 55' to the left against the pressure of the springs 57', thus 25 permitting the toggles 50 to be moved to unlocking position. By this arrangement it will be readily seen that the leveling plungers cannot fall accidentally, as would be the case were the pressure to cease owing 30 to the breakage in the air feed line or other causes.

It will be observed that our invention is in many respects fundamental and it will be apparent therefore, that departures can 35 be made from the mechanism shown and described, without departing from the spirit of our invention.

We claim:

1. A roll over molding machine comprising 40 in combination a marginally hinged roll over carrier adapted to support mold parts, a drawing mechanism over which the carrier is adapted to support the mold parts in inverted position, means for substantially relieving the roll over carrier of the weight 45 of the mold parts when in inverted position previous to the draw, and means to prevent the relieving force from exceeding the weight of the mold parts.

50 2. A roll over molding machine comprising in combination a marginally hinged carrier adapted to support mold parts, a drawing mechanism over which the mold parts are supported by the carrier when in inverted position, and means automatically leveling the mold parts with respect to the drawing mechanism and substantially relieving the carrier of the weight of the mold parts previous to the draw.

60 3. A roll over machine comprising a marginally hinged carrier having automatic clamping means for supporting mold parts, a drawing mechanism over which the mold parts are supported by the carrier when in inverted position, and a leveling device as-

sociated with the drawing mechanism for supporting mold parts during the draw, said leveling device also serving to maintain the plane of the carrier at right angles to the plane of movement of the drawing mechanism. 70

4. A molding machine comprising a marginally hinged carrier, a vertically movable drawing mechanism over which the mold parts are supported in inverted position by the carrier, and means associated with and actuated by the drawing mechanism for relieving the carrier of the weight of the mold parts previous to the draw. 75

5. A molding machine comprising in combination a marginally hinged carrier adapted to support mold parts, a drawing mechanism with respect to which the mold parts are brought into operative relation by the carrier, and drawing means bearing on the mold parts with a pressure substantially approximating the load pressure thereof whereby the carrier is substantially relieved of the weight of the mold parts preparatory to the draw and means to prevent the relieving force from exceeding the weight of the mold parts. 80

6. A molding machine comprising a vertically movable drawing mechanism, a carrier adapted to support the mold parts in operative relation with respect to the drawing mechanism, a leveling device associated with the drawing mechanism comprising a plurality of supporting members normally out of engagement with the flask, means for moving said supporting members independently into engagement with mold parts, and means for locking said supporting members. 95

7. A molding machine comprising a vertically movable drawing mechanism, a carrier adapted to support the mold parts in operative relation with respect to the drawing mechanism, a leveling device associated with the drawing mechanism comprising four cylinders in each of which is provided a plunger, means for introducing air into said cylinders to advance the plungers into engagement with mold parts, and means for locking said plungers. 100

8. A molding machine comprising a vertically movable drawing mechanism, a marginally hinged carrier adapted to support mold parts in operative relation with respect to said drawing mechanism, a head carried on said drawing mechanism, said head being provided with a plurality of plungers, means for advancing said plungers independently into engagement with mold parts to support the same, and means for locking the plungers. 110

9. A molding machine comprising in combination a pattern drawing mechanism, a roll over carrier mechanism adapted to support mold parts in operative relation with 120

- respect to said drawing mechanism, and a leveling device associated with said drawing mechanism comprising more than two supporting members, and a common means for supplying fluid pressure for advancing said supporting members independently into engagement with mold parts to support the same, said operating means being adapted to permit the supporting members to independently accommodate themselves to irregularities in mold parts.
10. In a molding machine the combination of a carrier adapted to support mold parts, a vertically movable drawing mechanism, means for advancing said drawing mechanism toward the mold parts, an automatic leveling device associated with the drawing mechanism, automatically operated when the drawing mechanism has moved a predetermined distance toward the mold parts.
11. A roll over drawing molding machine comprising in combination a drawing mechanism, a carrier adapted to support mold parts in operative relation thereto, a normally inoperative leveling device associated with the drawing mechanism, and means rendering said leveling device operative, said means being actuated by the movement of the drawing mechanism.
- 30 12. A molding machine comprising in combination a drawing mechanism, a carrier adapted to support mold parts in operative relation thereto, a leveling device associated with the drawing mechanism and adapted to be advanced into engagement with mold parts, means for operating the leveling device, and means carried by the drawing mechanism for automatically setting in operation said last mentioned means.
- 40 13. A molding machine comprising in combination a vertically movable drawing mechanism, a carrier adapted to support mold parts in operative relation thereto, a leveling device associated with the drawing mechanism comprising a plurality of cylinders each having a plunger adapted to be advanced into engagement with mold parts, a valve for admitting fluid pressure into said cylinders, and automatic means operable by the movement of the drawing mechanism for opening said valve.
- 50 14. A molding machine comprising in combination a carrier adapted to support mold parts, a drawing mechanism, a stop adapted to hold the carrier in operative position with respect to the drawing mechanism and means associated with the drawing mechanism for taking the load of the mold parts when in operative position without altering the position of the carrier determined by the stop.
- 60 15. The combination in a molding machine, a vertically movable drawing mechanism, a marginally hinged carrier adapted to support mold parts in inverted position above said drawing mechanism, an upwardly moving power means of a predetermined value not exceeding the weight of the mold parts associated with the drawing mechanism and adapted to substantially relieve the carrier of the weight of the mold parts previous to the draw.
16. The combination in a molding machine, a vertically movable drawing mechanism, a marginally hinged carrier adapted to support mold parts in inverted position above said drawing mechanism, an upwardly moving power means of a predetermined value not exceeding the weight of the mold parts associated with the drawing mechanism and adapted to substantially relieve the carrier of the weight of the mold parts previous to the draw, and means to lock said power means in operative position.
17. In a molding machine the combination of a vertically movable drawing mechanism, a marginally hinged carrier adapted to support mold parts in inverted position above the drawing mechanism, power means associated with the drawing mechanism adapted to substantially support the weight of the mold parts on the carrier, and means for varying the power exerted by said power means.
18. A molding machine comprising in combination a drawing mechanism, a carrier adapted to support mold parts in operative relation thereto, a fluid operated plunger adapted to engage mold parts to substantially relieve the carrier of the weight of such parts, and means for maintaining a predetermined pressure on said plunger.
19. A molding machine comprising in combination a drawing mechanism, a carrier adapted to support mold parts in operative relation thereto, and a combined leveling and supporting device associated with the drawing mechanism comprising a plurality of cylinders, a plunger in each cylinder adapted to be advanced into engagement with mold parts, a common source of fluid supply for said cylinders, and a pressure maintaining valve for said source of supply.
20. A molding machine comprising in combination a carrier adapted to support mold parts, a drawing mechanism comprising a main cylinder, a plunger in said cylinder movable a predetermined distance toward the mold parts, and a plurality of secondary cylinders, each provided with a plunger, said plungers being movable into engagement with the mold parts, the main plunger and the secondary plungers coming into operation successively.
21. A molding machine comprising in combination a carrier adapted to support mold parts, a drawing mechanism comprising a main cylinder, a plunger in said cylinder

der movable a predetermined distance toward the mold parts, a plurality of secondary cylinders, each provided with a plunger, said plungers being movable into engagement with the mold parts, the main plunger and the secondary plungers coming into operation successively, and a common means for operating all of said plungers.

22. In a molding machine, a carrier, a drawing mechanism, means for operating the same, and means for cutting down the speed of the drawing mechanism at the limits of its stroke.

23. In a molding machine a carrier, a pattern drawing mechanism comprising a cylinder and a plunger, one of which is provided with an oil reservoir, a passage for permitting flow of oil from the reservoir to the space beneath the plunger, means for introducing fluid pressure above the oil, and automatic means controlling the passageway, and adapted to restrict the flow through said passage at the limit of movement.

24. In a molding machine, a carrier, a pattern drawing mechanism comprising a cylinder and a plunger, one of which is provided with an oil reservoir, a passageway for conducting oil from the reservoir to the space beneath the plunger, means for introducing fluid pressure above the oil, and valve mechanism controlling said passageway adapted to close said passageway at the limit of movement.

25. In a molding machine a carrier, a drawing mechanism comprising a cylinder, a plunger, one of which is provided with an oil reservoir, a passageway for conducting oil to the space beneath the plunger, means for introducing fluid pressure above the oil, and means for arresting the upward movement of the plunger comprising an automatic valve adapted to close said passageway.

26. In a molding machine, a carrier, a drawing mechanism comprising a cylinder, a plunger, one of which is provided with an oil reservoir, a passageway for conducting oil to lower face of the plunger, means for introducing fluid pressure above the oil, and means for cushioning the plunger at the limit of movement.

27. A molding machine comprising in combination a roll over carrier adapted to support mold parts in inverted position with reference to a drawing mechanism, a leveling device comprising a plurality of leveling elements movable into engagement with the mold parts, a pressure actuated locking means for the leveling elements, and positive locking means for locking said first locking means.

In testimony whereof we have hereunto signed our names.

ABBOTT ALLEN.
THOMAS J. MUMFORD, 2d.
